9 Claims. Cl. 230—69

The present invention relates to vacuum pumping and particularly to the evacuation of vacuum systems by orbitron electron vacuum pumps (hereinafter "orbitron pumps"). There have been many attempts in the prior art to provide a convenient form of vacuum pumping device utilizing ionization and sorption effects. The orbitron pump accomplishes this without the direct use of magnets or cryogenics.

It is a principal object of this invention to provide an improved orbitron pump construction.

It is a further object of this invention to provide an improved technique of operating orbitron pumps.

The invention accordingly comprises the improved orbitron pump, the improved technique of operating orbitron pumps, as embodied in process and machine form, the application of the technique to my improved pumps and vacuum systems incorporating the above.

The invention is described below with reference to the accompanying drawings wherein:

FIG. 1 is a diagram of a vacuum system incorporating an orbitron pump;

FIG. 2 is an exploded partly sectional view of an improved orbitron pump according to a first species of my invention;

FIG. 2A is a sectional view of an assembled pump according to the same species as FIG. 2;

FIG. 3 is a sectional view of a portion of an orbitron pump according to another species of my invention;

FIG. 4 is a sectional view of a portion of an orbitron pump according to a further feature of my invention.

Referring now to FIG. 1, there is shown an evaporator system. This is an example of a vacuum system using the orbitron pump. A bell jar 10 is connected to a large (in comparison to the bell jar) diameter metal elbow 12 via sealed flanges 14. Several feedthroughs 16 are connected to the flanges for admitting electric wires, gases, mechanical levers, etc., into the bell jar for control of the coating process. A titanium filament 18 is mounted on the elbow for reducing the pressure of the system to below the level of pressure wherein it is difficult to start the orbitron pump. The orbitron pump 20 is connected to the elbow so that it has access to the bell jar 10 through a wide gas conductance path.

Also connected to the elbow 12 are an electric power supply 22 for heating the titanium filament 18 and a tube 24. A rotary mechanical pump 26 is connected to the tube via a valve 28. A cryosorption pump 30 is connected to the tube via valve 32. A valve 34 is provided for connection of a second cryosorption pump while the pump 30 is being regenerated. A valved connection 36 is provided for connecting a leak detector to the system. A tank 38 of inert gas is connected to the tube via valve 40 for backfilling the system to raise its pressure.

Referring now to FIG. 2, the pump 20 is shown in exploded fashion. The pump is made up of a flanged body 42 with cooling coils 44 welded to its outer wall and a cover plate 46 mounting a filament 48 and a central anode electrode 50. The electrode 50 includes a titanium slug 52. The pump operation is based on emission of electrons from filament 48. The electrons enter a radial electric field between the anode 50 and the wall 42 which is grounded to serve as a cathode. The electrons spiral around the anode 50 and eventually strike slug 52 providing a high heat input to the slug.

2

Titanium is sublimed from the heated slug and condenses on the cooled wall 42. Chemically active gases within the pump (oxygen, hydrogen, nitrogen, carbon dioxide, water vapor), are gettered by the condensed titanium. Inert gases in the pump are removed by the mechanism of ionization-collision of the gas molecules with electrons to form positive ions which are attracted to the wall 42 and subsequently buried by a fresh layer of titanium.

In prior art orbitron pumps the outer wall consists of a cylinder made of the usual materials preferred for construction of high vacuum devices. According to my invention, the usual wall construction is modified by the provision of radial fins 50 secured to the wall 42 by brazing, soldering or welding to give a good heat transfer connection. Clamping, for instance, is an unsatisfactory method of securing the fins to the wall because of the high heat transfer impedance of a demountable joint under conditions of high vacuum. The interior ends of the fins provide a virtual annular surface for purposes of controlling the electrostatic field of the pump. The fins may be made of the same width so that the virtual surface is cylindrical. The fins could be of different widths so that the virtual surface is elliptical or even irregular. The fins can also be tilted so that they cross several transverse or longitudinal radial planes rather than each lying in a transverse radial plane as in the preferred embodiment of FIGS. 2 and 2A.

Another species of my improved orbitron pump would be the use of titanium washers (not shown) welded to the pump wall or a long spiral of titanium, such as a lathe turning (shown as 350 in FIG. 3) welded to the pump wall.

The best mode of using my invention among the above species is the species of FIGS. 2-2A which offers higher gas conductance than the other.

A further and distinct improvement according to my invention is the use of tapered fins (450 in FIG. 4). Such a taper can be produced by machining or electro-polishing. The tapered form limits shadowing effects (with respect to the central source of titanium vapors) due to the use of the fins.

The invention is based on my observations of prior art orbitron pumps. These pumps tend to degrade in pumping speed characteristic after a long period of operation or after several pumpdown bakeout cycles. I attribute this to flaking of titanium deposits on the pump wall. The flakes have a poor thermal connection to the cooled pump wall and therefore afford a poorer sticking factor for subsequent titanium deposits and pumped gas molecules and ions. It is believed that in some instances the flakes tend to project randomly into the pump space and disturb the electrostatic field, thereby upsetting the conditions necessary to maintain orbiting of electrons.

The above species of my invention provide a solution to this problem (a) because of the substantial increase in pump wall surface area afforded thereby and (b) because the fins are made of titanium, titanium deposits will adhere readily to the fins. The welding of the fins to the wall assures good conditions of heat transfer to enhance the sticking coefficient.

Referring again to FIG. 2A, the pump is indicated, as assembled, with connections to power. There are two power supplies—a neon tube, high reactance transformer 60 for starting operations and a conventional power supply which may be D.C. or A.C. for running operation. Switches 62 and 72 are provided in series with the power supplies.

Referring again to FIG. 1, the pump-down cycle of the vacuum system can now be described. Initially, the system is at ambient pressure and all valves are closed. Valve 28 is opened and pump 26 is operated to pump

the system down to a pressure of about 10 microns Hg abs. or less. Then valve 32 is opened and sorption pump 30 is cooled to pump the system down to the 10^{-5} mm. Hg range. The elbow 12, bell jar 10 and pump 20 are subjected to a mild bake (100-200° C.). Then, after baking, the sublimator 18 is operated to pump the system down to 5×10^{-6} mm. Hg. The orbitron is then turned on by closing the switch 72 (FIG. 2A) and turning on the filament heater power supply (not shown). If the pump fails to take hold after a few minutes, then the filament power is cut off, switch 72 is opened and switch 62 is closed to establish an A.C. glow discharge between the anode and cathode of the pump. Argon may be bled in from tank 38 via valve 40 to assist in starting the glow discharge. After a few minutes the switch 62 can be opened to extinguish the discharge, valves 40 and 32 are closed, sublimator 18 is again operated to lower the pressure to 5×10^{-6} and the orbitron is re-started. Cooling water is admitted to the coils 44 of the pump. As the orbitron lowers the pressure, the emission current is gradually reduced for optimum usage of the titanium sources within the pump.

The above described glow discharge step improves adherence on the wall and fins and also activates the titanium surfaces within the pump for enhanced gettering action during the subsequent orbitron pumping step. This discharge step should be carried out between one and ten minutes.

The fins 50 (FIGS. 2, 2A), are $\frac{1}{32}$ - $\frac{1}{8}$ thick titanium having a width of $\frac{1}{4}$ - $\frac{1}{2}$ in., or about $\frac{1}{16}$ - $\frac{1}{8}$ of the pump diameter. The term diameter as used herein refers not only to the diameter of a cylindrical wall, but also to the average diameter of an elliptical or other form of annular pump wall. Typically, a 4 inch diameter pump would have about 40-50 fins $\frac{1}{2}$ inch in width and spaced about $\frac{1}{2}$ inch apart at the circumference of the pump. In general, the spacing between fins should be the same as their width and the number of fins is thus determined by this relationship.

The limits of $\frac{1}{16}$ - $\frac{1}{8}$ diameter for fin width correspond to effective use of the fins for the lower limit and minimal interference with orbiting electron operation for the upper limit. The virtual surface, formed by the inner edges of fins of $\frac{1}{8}$ diameter width, corresponds to an equipotential line of about $\frac{1}{10}$ total anode to cathode bias. In this arrangement, the fins do not prevent operation of the pump.

What is claimed is:

1. A vacuum pump, comprising, in combination, an annular wall, a central anode electrode, at least one electron source for injecting electrons into the space between the wall and central electrode, means for maintaining a

positive bias on the central electrode so that the electrons spiral about it, a source of reactive metal in the pump and reactive metal fins secured to the wall and extending radially inwardly toward the central electrode up to $\frac{1}{8}$ of the wall diameter, the fin surface area being at least as great as the inner surface area of the wall.

2. The pump of claim 1 further comprising means for establishing a glow discharge between the wall and central electrode.

10 3. Method of operating the pump of claim 2 comprising the steps of filling the pump with an inert gas to a pressure between 10^{-4} and 10^{-2} torr, striking a glow discharge between the wall and central electrode in the presence of said inert gas and subsequently extinguishing 15 the glow discharge and operating the pump with orbiting electron clouds.

4. A vacuum pump comprising, in combination, an annular wall, a central anode electrode, at least one electron source for injecting electrons into the space between

20 the wall and central electrode, means for maintaining a positive bias on the central electrode so that the electrons spiral about it, a source of reactive metal in the pump and reactive metal fins secured to the wall and extending inwardly toward the central electrode, the fins having 25 a width between $\frac{1}{16}$ and $\frac{1}{8}$ pump diameter and a spacing between fins about the same as the average width of the fins.

5. The pump of claim 4 wherein the fins are made of titanium.

30 6. The pump of claim 4 wherein the fins are pointed on their inner ends.

7. The pump of claim 4 wherein the fins are substantially vertical.

8. The pump of claim 4 wherein the fins are substantially horizontal.

35 9. The pump of claim 8 wherein the fins are formed of a continuous spiral.
